Patented Sept. 3, 1918.

FIG. 2

FIG. 3

By his Attorney, Inventor
Frank J. Quigan,
Alfred T. Dunn

UNITED STATES PATENT OFFICE.

FRANK J. QUIGAN, OF BROOKLYN, NEW YORK, ASSIGNOR TO SIMON ZINN INC., A CORPORATION OF NEW YORK.

CLASP FOR HAND-BAGS.

1,278,012.

Specification of Letters Patent.

Patented Sept. 3, 1918.

Application filed June 12, 1917. Serial No. 174,177.

To all whom it may concern:

Be it known that I, FRANK J. QUIGAN, a citizen of the United States, residing at Brooklyn, county of Kings, and State of New York, have invented certain new and useful Improvements in Clasps for Hand-Bags, of which the following, taken in connection with the accompanying sheet of drawings, is a full, clear, and concise description thereof.

This invention relates to clasps for hand bags and more particularly to a locking means for preventing the accidental opening of the bag.

It has for one of its objects the provision of a clasp locking means characterized by simplicity of construction and efficiency of operation.

Another object of the invention is the provision of a locking means which in one position will permit the clasp to be closed, but prevent its opening after once being closed.

A special object is the provision of a clasp, or locking means so constructed as to be capable of mounting substantially all of the parts thereof upon the exterior surfaces of the frame members of a bag, thus keeping the portions to which the body of the bag is secured free from obstructions which would otherwise be present if the operating parts of the locking means were located on the exterior surfaces of the frame members.

Other objects of the invention have to do with various features of construction and arrangement of parts hereinafter set forth and defined by the appended claims.

While I have herein shown and particularly described the preferred embodiments of my invention, I do not want to be limited to the precise details of construction illustrated, as changes may be made without departing from the spirit and scope of the invention.

Like reference characters refer to like parts throughout the several figures.

The invention is illustrated in the accompanying drawings, in which,

Figure 1 is a perspective view of a hand bag provided with my improved form of locking means.

Fig. 2 is a side elevation showing the frame members of the bag open, and the locking means conditioned to function.

Fig. 3 is a front elevation with the locking means functioning.

Fig. 4 is a similar view with the locking means rendered ineffective; and

Fig. 5 is a modification of the locking means shown in the other figures.

In the hand bag shown in the drawings, the numeral 1 designates the body of a hand bag provided with a frame 2, having sections or hinged members 3 and 4. Each of the hinged members is U-shaped in cross-section, and is likewise U-shaped in general configuration terminating in end extensions adapted to be pivoted together. The frame members 3 and 4 are secured to the body of the bag in any suitable manner, such as gluing, riveting and the like. Each of the members 3 and 4 is provided with a resiliently mounted knob member 5, said latter members being adapted to coöperate with each other in such a manner as to constitute what is ordinarily known as a knob clasp. The knobs 5 and their mountings form no part of the invention and may be made in any well-known manner. The locking means for holding the frame members 3 and 4 together, when closed, may comprise a resilient member 6 secured to the top surface of the frame member 4, and positioned transversely thereof. One end of the member 6 is flush with the exterior face of the frame member 4, and the other end terminates in a projecting convexly or downwardly curved portion 7, which extends sufficiently far so as to coöperate with a rotatably mounted stud or member 8. The stud 8 is provided with a collar 9, which forms the latch abutment, preferably formed integral therewith and adapted to contact with the exterior edge of the frame member 3. The journaling of the stud 8 in the frame member 3 is effected by the collar portion 9 abutting upon one side thereof and having the inner end of the stud spun over on the exterior surface. The exterior or projecting portion 10 of the stud 8 is provided with an aperture into which is fastened an actuating member 11, which may be of any conventional or ornamental configuration. The collar 9 has a portion 12 thereof removed so as to fit flush with the upper surface of the frame member 3 when the stud is suitably rotated. The location of this removed surface may be determined by the desired

positioning of the actuating member 11. In Figs. 1 to 4 it has an angular displacement of 180° relative to the actuating member 11, so that said member may occupy a vertical position relative to the frame member 3 when the locking mechanism is rendered ineffective by the removed collar portion 12 coming opposite the resilient member 6. The actuating member 11 may be provided with a suitable notation, such as "open" to indicate to the owner of the bag that the locking means is not functioning. It is obvious that by rotating the stud 8 by means of the actuating member 11 the frame members 3 and 4 may be held locked or unlocked together. Also, that the resilient member 6 may engage the collar 9 when its active or locking surface is in position for engagement therewith, thus permitting the automatic operation of the locking means when in a given position while requiring the manual manipulation thereof to permit the opening of the bag.

A modification of the stud 8 comprising a part of the locking means is shown in Fig. 5. In this modification the collar 9 is provided with two oppositely disposed inactive or removed surfaces 12, which are joined by a corresponding number of active surfaces. This form of construction permits the unlocking of the frame members 3 and 4 by rotating the actuating member 90°. At the same time it furnishes an automatic indication to the person carrying the bag as to the condition of the locking means, *i. e.*, if the actuating member 11 is vertically disposed, it will indicate that the bag is locked, whereas if it were turned out of the vertical position it would be an indication that the locking mechanism is not functioning. The latter condition would very likely be brought to the owner's attention because when the actuating member 11 approaches a horizontal position, it is very apt to become an obnoxious obstruction, and this feature would attract the attention of the owner.

While I have described my invention with reference to the specific embodiments shown, it is obvious that various changes in detail might be made without departing from the spirit and scope thereof.

What is claimed is:

1. A clasp for hand bags comprising a pair of frame members pivoted to one another at one end and adapted to fold against one another at the other end, a resilient latching plate secured to the free end of one of said pivoted members and disposed to extend across the free end of the other pivoted member when the members are folded against one another, and an abutment having a portion disposed to coöperate with said latching member when the pivoted members are folded against one another, said abutment being pivotally mounted on said other pivoted member in order to permit said portion to be moved into or out of engagement with said latching member.

2. A clasp for hand bags comprising a pair of frame members pivotally connected to one another, a latching plate secured to the free end of one of said frame members and disposed to extend across the free end of the other frame member when the frame members are folded against one another, an abutment pivotally mounted on that face of said other frame member which is removed from the first-mentioned frame member, said abutment having an active portion disposed to coöperate with said latching plate when the pivoted frame members are folded against one another, and said latch plate being of sufficient area to form a guard for the active portion of said abutment when in co-operation therewith.

3. A clasp for hand bags comprising a pair of frame members pivoted to one another at one end and adapted to fold against one another at the other end, a resilient latching plate secured to the free end of one of said pivoted members and having a concave portion extending across the free end of the other pivoted member when the members are folded against one another, and an abutment having an active portion disposed to coöperate with said concave portion when the pivoted members are folded against one another, said abutment being pivotally mounted on the exterior of said other pivoted member.

FRANK J. QUIGAN.
